UNITED STATES PATENT OFFICE.

JAMES D. ROSS, OF SEATTLE, WASHINGTON.

REFRIGERATING-MACHINE.

1,195,269.

Specification of Letters Patent. Patented Aug. 22, 1916.

Application filed September 6, 1913. Serial No. 788,390.

To all whom it may concern:

Be it known that I, JAMES D. ROSS, a citizen of the United States, and a resident of Seattle, in the county of King and State of Washington, have invented a new and Improved Refrigerating-Machine, of which the following is a full, clear, and exact description.

This invention relates to refrigerating systems of that type wherein the cooling is effected by the evaporation of a liquefied gas or the expansion of a compressed gas.

At the present time the only efficient refrigerants are very offensive, and in some instances poisonous, and heretofore it has been practically impossible to design and install a refrigerating system adapted for use in residences and business places because of the constant attention required to maintain the system gas-tight.

It is one of the objects of the present invention to provide an extremely simple, durable and efficient refrigerating system which automatically maintains a substantially uniform temperature and which does not require the care of an attendant except only occasionally for the purpose of inspection to see that the apparatus is operating at its best efficiency.

The place where leakage is most serious in present systems is at the pump or compressor, and to overcome all chances of leakage the present system contemplates the complete incasing of the pump and means for operating the same, so that there is positively no leakage of gas. The pump may be of reciprocating or centrifugal type, and the shaft thereof is preferably connected with the rotor of an induction motor. The pump and rotor of the motor are incased, and the sulfur dioxid, ammonia or other refrigerant is free to pass to the chamber inclosing the rotor, but leakage from such chamber to the atmosphere is absolutely prevented. The inclosing casing for the motor may be so designed as to include the stator as well as the rotor, as the refrigerant is anhydrous, and consequently rusting of the machine will not take place, and the windings for the rotor can be suitably protected to withstand the effect of the gas.

Another object of the invention is the provision of simple and effective means for controlling the starting, stopping and running of the motor in such a manner that the system will maintain a practically uni-

form temperature in the chamber or building intended to be cooled, there being used in connection with the motor controlling means, a device for opening and closing a flow of cooling water for the condensing coil of the system, so that when the motor is stopped or started the cooling water will be cut off or turned on.

An additional object is the employment of an aspirator in series with the centrifugal pump and cooling coil, whereby the continually pumped liquid sulfur dioxid, ammonia or other refrigerant, will entrap vapor and draw it out of the refrigerating coil and cause condensation of the vapor by the intermingling of the latter with the liquid in the condensing coil.

With such objects in view, and others as will appear as the description proceeds, the invention comprises various novel features of construction and arrangement of parts which will be fully set forth in the following description and claims appended hereto.

In the accompanying drawings, which illustrate certain embodiments of the invention, and wherein similar reference characters are employed to designate corresponding parts throughout the several views, Figure 1 is a diagrammatic view of the refrigerating system and controlling means therefor, with certain parts of the system in section; Fig. 2 is a sectional view of the refrigerating system including a multiple-stage centrifugal pump; and Fig. 3 is a fragmentary sectional view showing the entire motor incased.

Referring to the drawing, A designates the top or wall of a refrigerator or a room to be cooled, there being within the refrigerator or room a refrigerating coil B, which has the end 1 connected with a condensing coil 2 and the other end 3 connected with an aspirator C. A pipe 4 leads from the pipe 1 at a point between the coils B and 2 to a centrifugal pump D, the rotary element 5 of which is secured to a shaft 6 that is driven by an induction motor E. The rotor 7 of the induction motor is secured directly to the shaft 6, which latter is journaled in bearings 8 and 9. Surrounding the rotor is a stator 10 having energizing windings 11. The pump D is provided with a gas-tight casing 12 and the rotor 7 is inclosed in a gas-tight casing 13. Both of said casings have openings 14 and 15, respectively, through which the shaft 6

freely extends. The gaseous refrigerant is free to pass from the casing 12 into the casing 13, and as the bearings 8 and 9 are disposed respectively in the casings 12 and 13, the shaft does not require packings or stuffing boxes, since such shaft does not extend through the outer walls of the said casings. By this means it is obvious that there is no chance for the refrigerant to escape 5 into the atmosphere and become a menace to health. The centrifugal pump D is of any desired type, so that the details of construction need not be explained; and this pump is provided with a nozzle 16 which is disposed within the chamber of the aspirator C. This chamber 17 has a conical wall 18 provided with an expanding port or nozzle passage 19, and the contracted tip of the nozzle 16 is disposed close to and in alignment with the port 19. The pump draws 10 the condensed refrigerant from the condensing coil 2 through the pipe 4, and this liquid is discharged through the nozzle 16, which creates a suction in the chamber 17, and as such chamber 17 is connected with 15 the vaporizing or expansion coil B, the vapor from the latter is drawn out and caused to mingle with the liquid sulfur dioxide, and is consequently condensed in the coil 2. A contraction or choked passage 20 is provided in the pipe 1 at a point between the coil B and branch 4, and the liquid sulfur dioxide under high pressure abruptly expands in entering the coil B, and in expansion 20 absorbs heat units from the air surrounding the coil, in a manner well known.

The condensing coil 2, as well as part of the aspirator C, is cooled in any suitable manner, as for instance, by being inclosed 25 in a chamber 21 through which water flows. This chamber has a supply pipe 22 and a discharge pipe 23, and in the supply pipe is a valve 24 which is adapted to automatically open and close as conditions require. 30 The opening and closing of this valve are effected synchronously with the starting and stopping of the motor E, and, furthermore, these operations are accomplished preferably automatically, as by means of a 35 thermostat located in the chamber which is cooled by the refrigerating system. Hence, as shown in Fig. 1, the cooled chamber is provided with a thermostat 25 which is adapted to engage fixed contacts 26 and 27 40 at predetermined low and high temperature limits. The thermostat 25 is connected by a wire 28 with a supply main 29, and the contacts 26 and 27 are connected respectively to wires 30 and 31 which are in turn 45 respectively connected with the sections or windings 32 and 33 of the circuit-closing solenoid F, such windings 32 and 33 being connected by a wire 34 with the other supply main 35. The solenoid F has a core 36 that 50 carries a bridging contact 37 adapted to en-

gage contacts 38 and 39. The contact 38 is connected with the supply main 29, and the contact 39 is connected by a wire 40 with one terminal of the energizing windings 11 of the induction motor E. The other terminal of the field windings of the motor is connected by a wire 41 with the supply mains 35. When the temperature in the cooled chamber rises, the thermostat 25 engages the contact 27 and current then flows through 55 that circuit in which the winding 33 of the solenoid is included. The circuit closer for the motor is consequently closed so that the motor will start and cause the refrigerant to be pumped through the system. When 60 the cooled chamber is lowered in temperature to the required limit the thermostat 25 will engage the contact 26 and thereby close the circuits in which the winding 32 of the solenoid is included, such winding causing 65 the motor circuit closer to be opened, so that the pump will be stopped. The contacts 26 and 27 are connected respectively by wires 42 and 43 with sections 44 and 45 of the solenoid G, such windings being also connected with the supply main 35. The core 46 of the solenoid G is connected with a lever 47 of the valve 24, so that by means of the thermostat 25 the section 44 of the solenoid G will be energized when the valve 24 is to 70 be opened, while the section 45 will be energized when the valve is to be closed.

It is to be noted that the housing or casing 13 for the rotor of the motor may be made of non-conductive material, so that eddy currents will not be set up therein, but if a conductive material is used it should be of such high resistance that the losses due to eddy currents will be practically *nil*.

In Fig. 2 a modification is shown with 105 respect to the pump D' between the condensing coil 2 and refrigerating coil B. The pump is shown as a multi-stage centrifugal pump which serves to cause an effective circulation of the liquid and gaseous refrigerant without need of an aspirator. This pump is shown diagrammatically, but it is 110 to be understood that a pump of any suitable design will be satisfactory.

The modification shown in Fig. 3 resides 115 solely in the use of a gas-tight casing or housing 13^a for inclosing the entire motor, that is to say, the rotor and stator. As the refrigerant is anhydrous it has no injurious effects on the parts of the motor and the coils can be suitably protected so as not to be affected by the gaseous atmosphere in which the motor is enveloped. Obviously a reciprocating pump may be employed in connection with the induction motor, and in this case the pump and motor will be contained 120 in a gas-tight housing for the purposes hereinbefore mentioned.

From the foregoing description taken in connection with the accompanying draw- 125

ings, the advantages of the construction and method of operation will be readily understood by those skilled in the art to which the invention appertains, and while I have 5 described the principle of operation, together with the apparatus which I now consider to be the best embodiment thereof, I desire to have it understood that the apparatus shown is merely illustrative, and 10 that such changes may be made when desired as are within the scope of the appended claims.

Having thus described my invention, I claim as new and desire to secure by Letters Patent:

1. A refrigerating machine comprising a condensing coil, an expansion coil, an expansion means between the coils for causing the refrigerant to expand, in entering the 20 expansion coil, a pump having its suction side connected between the said means and condensing coil, an aspirator between the

delivery side of the pump and the condensing coil, and a connection between the expansion coil and aspirator whereby the latter draws off the expanded gas from the former.

2. A refrigerating machine comprising a condensing coil, an expansion coil into which refrigerant from the condensing coil expands, a rotary pump connected with both coils, and an aspirator connected with the discharge end of the expansion coil and receiving end of the condensing coil, and also connected with the pump, whereby the fluid 30 discharged from the latter will draw the expanded gas from the expansion coil.

In testimony whereof I have signed my name to this specification in the presence of two subscribing witnesses:

JAMES D. ROSS.
